DESIGN FOR A LANTERN

Michael J. Freemark, Breckenridge, Minn.

Application November 18, 1939, Serial No. 88,366

Term of patent 7 years

To all whom it may concern:

Be it known that I, Michael J. Freemark, a citizen of the United States, residing at Breckenridge, in the county of Wilkin and State of Minnesota, have invented a new, original, and ornamental Design for Lanterns, of which the following is a specification, reference being had to the accompanying drawing forming part thereof.

The figure is a perspective view of a lantern, showing my new design.

The dominant feature of my design resides in the portions shown in full lines. The lantern has substantially the same appearance on both sides.

I claim:

The ornamental design for a lantern, as shown and described.

MICHAEL J. FREEMARK.
